(57) CLAIM

The ornamental design for a chair, as shown and described.

DESCRIPTION

FIG. 1 is a top, front, left-side perspective view of a chair showing my new design;

FIG. 2 is a bottom, rear, right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a partial and enlarged view thereof, in which the area of enlargement is portion 9 in FIG. 5; and,

FIG. 10 is a partial and enlarged view thereof, in which the area of enlargement is portion 10 in FIG. 6.

The dot-dash broken lines of FIGS. 5-6 and 9-10 are included to show the partially enlarged views only and form no part of the claimed design.

1 Claim, 10 Drawing Sheets
